CLAIM

The ornamental design for a video display pedestal, as shown and described.

DESCRIPTION

FIG. 1 is a front perspective view of a video display pedestal showing my new design;

FIG. 2 is a top plan view thereof;

FIG. 3 is a front elevational view;

FIG. 4 is a left side elevational view thereof, the right side elevational view being a mirror image thereof;

FIG. 5 is the rear elevational view thereof; and,

FIG. 6 is a perspective view thereof, with a broken line depiction of a video display unit being shown for illustrative purposes only and forming no part of the claimed design.
